(57) **CLAIM**

The ornamental design for an electronic copying machine display screen with graphical user interface, as shown and described.

DESCRIPTION

The patent or application file contains at least one drawing executed in color. Copies of this patent with color drawing(s) will be provided by the Office upon request and payment of the necessary fee.

FIG. 1 is a front view of an electronic copying machine display screen with graphical user interface showing our new design; and,

FIG. 2 is a front view thereof, with the alphanumerical and graphical characters removed for clarity of illustration.

The dash dot dash line showing the display screen forms no part of the claimed design. The broken line showing of the remainder of the graphical user interface and the electronic copying machine forms no part of the claimed design.
